PHONOGRAPH

Edward F. Andrews, Chicago, Ill.

Application April 22, 1931, Serial No. 531,860

46 Claims.

(Cl. 274—10)

This invention relates to phonographs and particularly to phonographs which are adapted to play series of records in succession.

One of the objects of the invention is to provide a table adapted to receive a series of records adapted to be engaged by a depressible pin which is resiliently pushed outwardly.

A further object of the invention is to provide a depressing pin adapted to depress the depressible pin and remove the record from the table, the effective length of said depressing pin being adjustable to accommodate records of various sizes.

A further object of the invention is to provide a depressible pin for engaging records upon a table and adapted to be depressed with slight frictional resistance.

A further object of the invention is to provide a depressing pin formed to permit easy engagement with the record and avoid wear thereof.

A further object of the invention is to provide means whereby any particular record may be repeated as often as desired.

Other objects, advantages and capabilities of the invention will hereinafter appear from the following description of a preferred embodiment thereof, taken in conjunction with the accompanying drawings, in which

Figure 1 is a sectional elevation of a phonograph embodying the invention;

Fig. 2 is a sectional plan thereof, taken on the line 2—2 of Fig. 1;

Fig. 3 is a front elevational view of the pick-up head in central relation with respect to a series of records and associated elements which are shown in section;

Fig. 4 is a sectional detail on a large scale taken on the line 4—4 of Fig. 3;

Fig. 5 is a sectional plan taken on the line 5—5 of Fig. 4;

Fig. 6 is a developed elevation of the depressing pin shown in Figs. 3 and 4;

Fig. 7 is an elevation, partly in section, showing a modified form of adjustable depressing pin;

Fig. 8 is a similar view of a further modification;

Fig. 9 is a sectional detail on the line 9—9 of Fig. 8;

Fig. 10 is an inverted plan on the line 10—10 of Fig. 8;

Fig. 11 is a front elevational view of a pick-up provided with means to permit a particular record to be repeated;

Fig. 12 is a side view thereof.

Fig. 13 is a sectional detail view of a further form of adjustable depressing pin.

Fig. 14 is a plan view of a collar employed therein.

Fig. 15 is an elevational view of same collar.

Fig. 16 is an inverted plan detail of the stirrup; and

Fig. 17 is a sectional detail of the lower end of the depressing pin taken at the line 17—17 of Fig. 13.

The present invention is particularly applicable to phonographs in which a superimposed series of records are placed upon a table, for example a turntable, which is provided with a depressible pin, which projects through the central openings of the records, and which is provided with an actuating arm for removing the records from the table seriatim, which arm carries a depressing pin adapted to depress the depressible pin, engage the top record through its opening, and remove said record.

For convenience I will describe the invention in connection with the phonograph described, and claimed in my co-pending application Serial No. 494,560, filed November 10, 1930, in which the tone arm is actuated to effect the record removal. It must be understood, however, that I do not intend to be limited to such structure except when set forth in the accompanying claims.

Referring to the drawings, the numeral 10 designates phonograph records which are stacked in desired number upon a turntable 11 which is driven from a suitable motor (not shown) through a gear 12 rigidly carried on its underside. The turntable 11 is rigidly mounted on the upper end of a spindle 13, which is rotatably mounted in the mechanism framework. The spindle 13 is hollow 30 and receives the hollow pin 14 which is normally projected above the table 11 for a substantial distance by means of an enclosed coil spring 15, so as to enter the central openings of the records 10. The pin 14 is preferably slightly tapered so 35 as to reduce the friction opposing its depression.

The spindle 13 carries an integral gear 16, by means of which the player arm 17 is actuated to remove the records after they are played. The gear 16 engages a gear 18 mounted on a spindle 19 which also carries a gear 20. The gear 20 engages a gear 21 which is rigidly secured to a notched wheel 23 and to a spacer disk 24 interposed therebetween. The assembly 22, 23, 24 is freely mounted upon a spindle 25. The spindle 25 rigidly carries a disk 26 and two cams 27 and 28. The disk 26 carries a spring pressed pawl 29 which is adapted to engage the notched wheel 23 and clutch same to the spindle 25, except when said pawl is engaged by the pin 30 as hereinafter described.

The cam 27 is engaged by a cam roll 31 which is carried by the link 32, one end of which is pivotally secured to a stepped disk 33. The other end of the link 32 is bifurcated and slides in a 55 groove provided by sleeves on the spindle 25. The disk 33 is pivotally supported upon a boss 34 which depends from a support 35 which is mounted upon the motor board 36. The support 35 is provided with a vertical bore which 60

provides a bearing for a hollow stem 37. At its upper end the stem 37 carries a rearwardly extending arm 38 to which the rear end of the player arm 17 is pivotally secured. A spring 39 is provided to counterbalance the weight of the player arm 17.

A rod 40 is pivotally connected to the player arm 17 and extends downwardly through the hollow stem 37, its lower end being reduced to provide a shoulder 41 which engages a bell crank lever 42 pivotally mounted on the mechanism frame as shown at 43. The bell crank lever 42 is pivotally connected to a link 44, the forward end of which is bifurcated and slides in a groove 15 provided in a sleeve mounted on the spindle 25. The link 44 carries a cam roll 45 which cooperates with the cam 28.

The pin 30 is carried on the underside of a bar 46 which is bifurcated at one end to slide in a groove provided in a sleeve mounted on the spindle 25. The other end of the bar 46 is provided with a slot 47 which receives the reduced end of a pin 48 so that the bar 46 may slide longitudinally. A tension spring 49 connected to the bar 25 46 and the pin 48 tends to draw the bar away from the pawl 29 with the pin 30 out of the path of said pawl.

A sector arm 50 is rigidly carried by the lower end of the hollow stem 37. The sector has an outer arcuate edge 51 and an arcuate slot 52, the inner edge of which is cut away at its open end as shown at 53. A pin 54 projecting from the upper side of the bar 46 is adapted to enter the slot 52. As the player arm 17 is moved to initial playing position the sloping surface 53 engages the pin 54 and moves the bar 46 to the left as viewed in Figs. 1 and 2 and brings the pin 30 into the path of the projecting tail of the pawl 29 so that said pawl is disengaged from the 40 notched wheel 23 when said wheel rotates the pawl 29 into engagement with the pin 30.

A pawl 55 pivotally mounted on the bar 46 is provided with a projection 56 which is adapted to abut against the edge 51 of the sector 50. The 45 opposite end of the pawl 55 carries a projection 57 which is normally held against an abutment 58 by means of a spring 59 so as to keep the projection 56 directed towards the edge 51.

When the player arm moves towards initial 50 playing position and the bar 46 is moved to the left as described above, the pawl 55 is engaged by the edge 60 of the sector and then rotates into the position shown in Fig. 2. The spindle 25 continues to rotate until the pawl 29 makes contact with the pin 30, whereupon the spindle is 55 operatively disconnected from the wheel 23. During the first portion of the playing of the record the bar 46 is maintained in its left hand position by the engagement of the pin 54 with the inner edge of the slot 52. When the pin enters the flared end of the slot 52, the pawl 55 keeps the bar 46 in the left hand position. If the record ends in a spiral groove the pawl 55 overruns the edge 60 of the sector and the pawl 60 29 is released. If the record ends in an eccentric groove, the first reverse movement of the sector 50 topples the pawl 55 and the pawl 29 is released. When the pawl 29 is released it engages the next notch of the rotating wheel 23 65 and the spindle 25 rotates one revolution until the pawl 29 again engages the pin 30, which at that time has returned to its pawl engaging position.

75 An annular member 61 is mounted on the mo-

tor board 36 concentrically with respect to the disk 33. The member 61 carries two radial arms 62 and 63, the former of which carries a pin 64 which projects through a slot 65 in the motor board 36. This pin may be secured to the motor board by a suitable nut (not shown) and its position in the slot 65 adapts the machine for records of different sizes. The radial arm 63 carries a depending pin 66 which is adapted to engage the rear end of a pawl 67 mounted on the sector arm 50. The forward end of the pawl 67 is adapted to enter a notch 68 in the edge of the disk 33 at the beginning of or during the playing period.

A spring 69 secured to the motor board 36 and 15 to a pin 70 which depends from the disk 33 normally tends to rotate the disk in clockwise direction as viewed in Fig. 2. A collar 71 depending from the sector arm 50 prevents the link 72 connecting this spring from passing through dead 20 center. The disk 33 carries a depending pin 73 which is adapted to engage the sector 50 to actuate the player arm. The pivot pin 74 of the pawl 67 projects below the sector arm 50 and is adapted to be engaged between the diverging 25 limbs of a spring 75 to resiliently arrest the thrown player arm and associated parts.

The player arm 17 carries a suitable pick-up 76 provided with a stylus 77. A stirrup 78 pivoted to the sides of the pick-up 76 is adapted to 30 swing below the stylus and is provided with a brush or the like 79 which protects the record from injury by the stirrup 78 during playing and at the same time cleans the record. The stirrup 78 carries a depressing pin 80 which will be hereinafter more particularly described. The nature of the cams 27 and 28 will more readily be understood if described in connection with the operation of the machine.

The operation is as follows: The machine is 40 shown in the initial playing position, the turntable 11 is rotating, the top record 10 is being played and the shaft 25 is at rest, the pawl 29 being held out of engagement with the notched wheel 23. After playing the pawl 29 is released 45 in the manner described above and the shaft 25 is driven through one revolution which effects the removal of the top record 10.

At the beginning of the revolution, the cam roller 45 rides upon a rise 81 on the cam 28 and 50 the player arm 17 is elevated from the record. The cam roller 31 then passes over a cam fall 82 on a cam 27 and the spring 69 rotates the arm 17 about its vertical axis, the cam rest 83 arresting the movement when the pin 80 is in the 55 plane of the pin 14 and shaft 31.

The cam roller 45 then rides down a fall 84 on the cam 28 and the player arm 17 is lowered so that the pin 80 depresses the pin 14 for a distance approximately the same as the thickness of 60 a record. The cam roller 31 then overruns the cam rest 83 and the spring 69 throws the player arm 17 and played record 10 laterally and the record is received in a suitable receptacle (not shown).

The cam follower 45 then rides up a cam rise 86' so that the player arm is returned to initial 65 playing position. The arm is arrested at such position by the engagement of the pawl 67 with the pin 66 which is adjustable as described above 70 to play records of desired size.

I will now describe in detail the pin 80 and associated elements. I prefer to provide means whereby the effective length of the pin may be varied at will to adapt it to cooperate with 75

records of different thicknesses. At present there are on the market records approximately one-tenth of an inch thick and records one-thirty second of an inch thick, and it is expected 5 that records of smaller thickness will come into use owing to their outstanding advantages with respect to storage space and amount of material in the record.

In the modification shown in Figs. 3, 4 and 6, 10 the pin 80 is freely mounted in a bore in the stirrup 78 and is provided with a head 86 whereby it may be adjusted by hand. The underside of the head 86 is engaged by a leaf spring 87 which normally presses the pin 80 upwards. The pin 80 is provided with a circumferential slot 88, a developed view of which is shown in Fig. 6. This slot opens into a plurality of downwardly directed recesses 89, 90, 91 and 92 which are located at different levels. A screw 94 extends 15 through the stirrup 78 into the slot 88 and is adapted to be brought into any of said recesses to vary the projection of the pin 80 beyond the shoulder 95 of the stirrup. Thus when the screw 94 is in the recess 89 the pin 80, may, for example, project downwardly one-tenth of an inch; when it is in recess 90 the pin may project downwardly one-thirty second of an inch; when the screw 94 is in the recess 91 the pin may project downwardly one-hundredth of an inch; and when 20 the screw is in the recess 92 the pin may be flush with the shoulder 95 so that the pin 80 does not depress the pin 14, the top record is not removed but is played repeatedly as long as desired. It will readily be understood that the pin 80 may be brought into any position of adjustment by merely depressing it again.

In Fig. 3, I show further means for effecting repeated playing of any particular record. This means consists of a small cap 96 which is applied to the top of the pin 14. This cap has a flange 97 which projects over the top record around the central opening therein. It will readily be understood that when the player arm descends in the center of the record, as above described, the pin 80 engages the cap 96. When the flange 97 engages the top of the record the depression of the pin 14 is arrested and the player arm moves laterally and then returns to initial playing position without removing the top record. Upon removal of the cap 96, the normal playing 50 of the records 10 is resumed.

As shown in Fig. 5 it is preferred to form the lower end of the pin 80 somewhat smaller than the central openings of the records so that it 55 may readily enter into same. In order to minimize wear of the record by the pin 80, I prefer to form the end of the pin 80 of the cross section shown in Fig. 5 with cylindrical faces of the same curvature as the record openings.

In the modification shown in Fig. 7, the pin 80 is threaded into the stirrup 78 and is provided with a kerf 98 to permit adjustment. The pin is provided with a head 99 which limits the downward projection of the pin to an amount 60 substantially equal to the thickness of the thickest records intended to be used. The lower end of the pin 80 is shouldered as shown at 100, which shoulder may limit the inward position of the pin so that its underface is substantially 65 flush with the shoulder 95 of the stirrup so as to prevent depression of the pin 14 and permit any record to be played repeatedly. Lines 101 and 102 may be scored on the lower end of the pin at suitable positions so that when same are brought into the plane of the shoulder 95, the pin 70

is adjusted for standard thin records. In order to avoid excessive size of the stirrup 78, the pin 80 may be offset relatively to the stylus 77 and the cam 27 is accordingly modified to bring the pin 80 into cooperative relation to the pin 14. 5

In the modification shown in Figs. 8, 9 and 10, the stirrup 78 is mounted upon lugs 103 carried by the underside of the pick-up 16 on one side of the stylus 77. In this modification the pin 80 is freely movable in an opening in the stirrup and 10 is normally pressed upwardly by a spring 87, which may be a coiled spring, acting upon the underside of the head 86. The pin 80 rigidly carries a laterally projecting pin 104 which is adapted to enter radial slots 105, 106, 107 and 15 108, cut in the face or shoulder 95 of the stirrup 78. These slots are of various depths to provide adjustment of the projection of the pin 80 as described above in connection with the modification shown in Figs. 3, 4 and 6. It will readily 20 be understood that such projection may readily be modified by depressing the pin 80 against the action of the spring 87 and rotating it to bring the pin 104 into the desired slot.

In Figs. 11 and 12, I show a further embodiment of the invention comprising means for preventing the removal of any particular record and causing same to be played repeatedly. In this embodiment I pivotally support a second stirrup 109 upon the pick-up 16 so that it will interpose 25 a flat bar 110 between the pin 80 and the pin 14 so that the latter is not depressed below the top plane of the top record. The stirrup 109 may be held in an elevated position by a clip 111 to permit the playing and removal of records serially in the normal operation of the machine. 35

In Figs. 13 to 17, I show a further embodiment of the adjustable depressive pin, in which the pin 112 is rigidly carried by the stirrup 113. The pin 112 may be secured in position by means of 40 a pin 114 which is driven into the stirrup and pin 112 after the collar 115 and spring 116 are mounted thereon. The pin 112 is provided with an enlarged head 117, which has a sliding fit in the bore of the collar. The upper side of the collar is cut away to provide opposite pairs of seats 118, 119, 120 and 121, located circumferentially in order of depth. The two fingers 122 formed by sets of seats are separated by residual parts of the collar which overhang the head 117 of the 50 pin 112 and prevent removal of the collar therefrom. The fingers 122 bear against the upper reduced portion of the pin 112 and provide upper bearings for the collar.

The stirrup 113 carries diametrically opposite 55 teeth 123 which are adapted to engage the seats 118, 119, 120 and 121, so as to vary the effective length of the pin 112, that is, the amount of the pin which projects below the lower face of the collar 115. The collar is pressed upwardly 60 against the teeth 123 by the spring 116, which bears against the underside of the fingers 122. The head 117 is preferably provided with an annular groove 125 to receive the lower portion of the spring 116. 65

As will readily be seen from the drawings, between the adjacent seats 118, 119, 120 and 121, the collar is provided with sloping facets to facilitate the rotation of the collar to move the teeth 123 from one seat to the next. These 70 facets extend above the level of the adjacent seats slightly so as to prevent accidental rotation of the collar.

The collar is provided with a handle 126 whereby it may be rotated from one position of ad- 75

justment to another, with the aid of slight downward pressure. The seats 118, 119, 120 and 121 are located at different levels to provide the desired effective lengths of depressing pin. Thus the engagement of the teeth 123 with the deepest seats 118 permits the pin 112 to project one-tenth of an inch below the lower surface of the collar to adapt the machine to composition records of standard size. When the teeth engage 10 the seats 119, the extent of projection of the pin 112 is decreased to adapt the machine to play records at, for example, one-thirty-secondth of an inch thickness. When the teeth engage the seats 120 the machine is adjusted to play records 15 of say one-hundredth of an inch in thickness. Finally when the teeth engage the seats 121, the pin 112 no longer projects below the lower surface of the collar and the top record is repeatedly played until the collar is again adjusted.

20 The head 117 of the pin 112 may suitably be of the same size as the opening in the records. Its lower end, which enters the record openings, is cut away so as to render it smaller than said openings, leaving the portion 127, which engages 25 the record during removal, of the original curvature.

It is to be understood that the invention is not limited to a machine in which the tone arm is used to effect record removal since other means 30 may be employed for the purpose. Furthermore, such means are not necessarily automatic. They may, for example, be operated by hand, or by means of manually actuated means.

Although the invention has been described in 35 connection with the specific details of preferred embodiments thereof, it must be understood that such details are not intended to be limitative of the invention except insofar as set forth in the accompanying claims.

40 Having thus described my invention, what I claim as new and desire to secure by Letters Patent is:

1. In a phonograph, in combination, a table adapted to support a stack of records, a depressible pin adapted to extend through the openings therein, means to depress said pin to permit removal of a record, and said pin being slightly tapered along its length to reduce friction opposing said depression.

50 2. In a phonograph, in combination, a table adapted to support a stack of records, a depressible pin adapted to extend through the openings therein, resilient means normally projecting said pin outwardly and means to depress the pin by 55 exteriorly applied force, said pin being tapered slightly along its length to reduce friction opposing said depression.

3. In a phonograph, in combination, a turn-table adapted to support a stack of records, a depressible pin adapted to extend through the openings therein, a spring normally projecting the pin outwardly, and means to depress said pin to permit the removal of a record, said pin being tapered slightly along its length to reduce friction 65 opposing said depression.

4. In a phonograph, in combination, a turn-table adapted to support a record having a circular opening, a pin capable of translatory movement over said table and adapted to enter said opening, said pin being smaller than said opening and provided with a face of substantially the same curvature.

5. In a phonograph, in combination, a table adapted to support a stack of records, a depressible pin adapted to project through the open-

ings thereof, a pin adapted to engage said depressible pin, a shoulder associated with said depressing pin adapted to engage the surface of the top record to limit the entry of said depressing pin into the record opening, and means 5 for modifying the effective projection of the depressing pin beyond the shoulder.

6. In a phonograph, in combination, a table adapted to support a stack of records, a depressible pin adapted to project through the openings thereof, a depressing pin adapted to engage said depressible pin, means associated with said depressing pin adapted to engage the surface of the top record to limit the entry of said depressing pin into the record opening, and means for 10 affecting the effective length of the pin to adapt same for use with records of varying thickness.

7. In a phonograph, a table adapted to support a series of records, a depressible pin extending through the openings therein, means for 20 depressing said pin to remove a record, and means adapted to be interposed therebetween to prevent removal of said record.

8. In a phonograph, a table adapted to support a series of records, a depressible pin extending through the openings therein, a depressing pin adapted to depress the depressible pin and remove the top record from the table, and a flanged cap adapted to be mounted on the depressible pin to prevent removal of said record. 25

9. In a phonograph, a table adapted to support a series of records, a depressible pin extending through the openings therein, an arm, a depressing pin carried by said arm adapted to depress the depressible pin and remove the top 35 record from the table, and a member pivotally mounted on the arm to swing below the depressing pin when it is desired to repeat the playing of a record.

10. In a phonograph, in combination, a table 40 adapted to support a stack of records, a depressible pin adapted to project through the openings thereof, a pin adapted to engage said depressible pin, a collar mounted on said depressing pin adapted to engage the surface of the top record to limit the entry of said depressing pin into the record opening, and means for maintaining the collar in a plurality of positions with respect to the depressing pin. 45

11. In a phonograph, a player arm, means suspended therefrom carrying a pin, movable means associated therewith adapted to modify the effective length of said pin, a table adapted to support a plurality of records, a depressible pin adapted to project through the openings in the records, and means for actuating the depressing pin to depress the depressible pin and remove the record from the table. 50

12. In a phonograph, a table for records, a depressible pin adapted to extend through the records, a depressing pin adapted to cooperate therewith, and means relatively movable with respect to the depressing pin to vary its effective length. 60

13. In a phonograph, a table for records, a depressible pin adapted to extend through the records, a depressing pin adapted to depress said depressible pin, an arm carrying the depressing pin, and means for actuating the arm in the vertical and transverse directions to depress the 70 depressible pin and remove the top record, and means for adjusting the effective length of the depressing pin. 65

14. In a phonograph, a table for records, a depressible pin adapted to extend through the 75

records, a depressing pin adapted to depress said depressible pin, a player arm carrying the depressing pin, means for actuating the arm in vertical and transverse directions to depress the depressible pin and remove the top record, and means for adjusting the effective length of the depressing pin.

15. In a phonograph, a table for records, a depressible pin adapted to extend through the records, a depressing pin adapted to depress said depressible pin, a stirrup carrying the depressing pin, a pick-up on which said stirrup is pivotally mounted, a player arm carrying the pick-up, means for actuating the player arm in vertical and transverse directions to depress the depressible pin and remove the top record, and means for adjusting the effective length of the depressing pin.

16. A record changer phonograph including a rotating turntable adapted to carry a stack of records, a movable center pin upwardly biased to project above the uppermost of the stack of records on the turntable during the playing operations, and means to depress the center pin so that its upper end is positioned at the lower surface of the uppermost record, to free said uppermost record for removal between playing operations.

17. A record changer phonograph including a rotating turntable adapted to receive a pile of records, a depressible center pin therefor, means for depressing the pin so that its upper end is positioned at the lower surface of the topmost record, to free said topmost record on the turntable, means for removing the topmost record between playing operations, and resilient means operating between playing operations for again raising the pin above the remaining records.

18. In a phonograph, in combination, a rotating turntable adapted to support a stack of records, a pin adapted to extend through openings therein, means adapted to depress said pin so that its upper end is positioned substantially at the lower surface of the topmost record and to remove said topmost record by lateral sliding movement, and resilient means adapted to force the pin upwards after said removal.

19. In a phonograph, in combination, a rotating turntable adapted to support a stack of records, a pin adapted to extend through the openings therein above the surface of the top record, record removing means adapted to enter the opening of the top record, depress the pin so that its upper end is positioned at the lower surface of the topmost record and remove said topmost record by lateral sliding movement, and resilient means adapted to force the pin upwards above the surface of the new top record after said removal.

20. In an automatic phonograph, a rotating turntable, a depressible pin adapted to center a stack of records thereon, spring means normally forcing the depressible pin upwardly, an arm adapted to move above said record stack, a magazine located laterally of, and below, the turntable and adapted to receive played records, and operative means for actuating said arm to cause it to move to depress said pin, engage the topmost record of said stack and slide it off, while the record therebeneath is held centered by said pin, to raise said arm and return same to its initial position and to repeat said operations upon the record next below the topmost record after said next record has been played.

21. A phonograph comprising a player arm, a turntable adapted to support a stack of records,

a motor for rotating the turntable continuously during the playing of said stack, a depressible pin in said turntable projecting through the center holes of said records, spring means normally biasing the depressible pin to a position in which its upper end is above said records, an arm carrying a depressing pin adapted to depress said depressible pin, means associated with the depressing pin for engaging the topmost record to limit the entry of the depressing pin to a distance substantially the thickness of a record, means for swinging said arm transversely of the turntable to slide off said topmost record, a receptacle adjacent the turntable to receive the removed records, means for raising the arm and returning it to engage the next record, and means controlled by the player arm for initiating the record removal movements of the first said arm.

22. In a phonograph, in combination, a rotating turntable adapted to support a stack of records, a depressible center pin passing through the holes in said records, resilient means normally tending to force the depressible pin upwardly with its upper end above the records, means above the turntable for depressing said pin just enough to free the top record, the records below the top record being held in place by the depressible pin, and means for sliding the top record off the stack.

23. In an automatic phonograph, in combination, a record supporting means, a depressible pin for centering a stack of records on said supporting means, a member above said record supporting means, actuating means for said member for causing it to depress said pin and slide the topmost record off said stack while the records therebeneath are held centered by said pin, resilient means biasing the pin upwardly whereby it is caused to bear against the topmost record during removal and to project above the remaining records after said removal.

24. In combination, a phonograph comprising a rotating turntable adapted to support a stack of records, a depressible pin extending through said records, means movable above the stack having a limited entry into the opening of the top record for freeing said record, means for causing said record to slide off the stack, and resilient means biasing said pin upwardly.

25. In combination, a phonograph comprising a rotating turntable adapted to support a stack of records, a depressible pin extending through said records, means having a limited entry into the opening of the top record for freeing said record, means for causing said record to slide off the stack, and resilient means biasing the depressible pin upwardly against said depressing means, and against the topmost record during its removal and causing it to project upwardly above the rest of the stack after said removal.

26. In combination, a phonograph comprising a rotating turntable adapted to support a stack of records, a centering pin depressible from above extending upwardly through the central openings of said records, spring means biasing said pin upwardly, a pin movable above the stack of records, means for causing said movable pin to enter the opening of the topmost record, means associated with said movable pin limiting the entry of the movable pin to free the topmost record only, and means for moving the said movable pin transversely to cause the topmost record to slide over the surface therebeneath and thereby effect the removal of the topmost record from the stack.

27. In an automatic phonograph, in combination, a support for a stack of records, a centering

pin on said support adapted to project through the openings of said records, resilient means biasing said pin outwardly from the support so as to cause it to project beyond said records, record 5 removing means, means actuating said record removing means to depress said pin just sufficient to free the topmost record therefrom and to cause it to move laterally thereby causing said topmost record to slide over the top of the record therebeneath.

28. A record changer phonograph including a rotating turntable adapted to carry a stack of records, a movable center pin upwardly biased to tend to project above the uppermost of the stack 15 of records on the turntable, and means for engaging the uppermost end of said center pin to depress it so that said upper end is positioned substantially at the lower surface of the uppermost record to free said uppermost record for 20 removal between playing operations.

29. A record changer phonograph including a rotating turntable adapted to receive a pile of records, a depressible center pin therefor, means for engaging the uppermost end of said pin and depressing it so that its upper end is positioned substantially at the lower surface of the topmost record to free said topmost record on the turntable, means for removing the topmost record between playing operations, and resilient means 30 operating between playing operations for again raising the pin above the remaining records.

30. In a phonograph, in combination, a rotating turntable adapted to support a stack of records, a depressible center pin passing through 35 the holes in said records, resilient means normally tending to force the depressible pin upwardly with its upper end above the records, means movable above the turntable for engaging the top of said pin and depressing it just enough to free the 40 top record, the records below the top record being held in place by the depressible pin, and means for sliding the top record off the stack.

31. In an automatic phonograph, in combination, a rotating turntable, a depressible pin for 45 centering a stack of records on said turntable, a member above said turntable, actuating means for said member for causing it to engage said pin to depress said pin and slide the topmost record off said stack while the records therebeneath are 50 held centered by said pin, resilient means biasing the pin upwardly whereby it is caused to bear against the topmost record during removal and to project above the remaining records after said removal.

55. 32. In an automatic phonograph, in combination, a rotating turntable adapted to support a stack of records, a centering pin on said turntable adapted to project through the openings of said records, resilient means biasing said pin outwardly from the turntable so as to cause it to project beyond said records, record removing means, means actuating said record removing means to cause it to engage and depress said pin just sufficient to free the topmost record therefrom and to cause it to move laterally, thereby causing said topmost record to slide off over the top of the record therebeneath.

33. In an automatic phonograph, in combination, a turntable located in a fixed plane adapted 70 to receive a stack of records to be played, driving means for continuously rotating the turntable during playing and record removal, said turntable having a spindle provided with a central bore, a depressible pin slidably mounted in said 75 bore, a spring within said bore normally pro-

jecting the pin through the openings in the records and substantially above said turntable, a pivotally mounted depressing member movable above said turntable and capable of moving downwardly by gravity through the space occupied by 5 the stack of records, means for holding said depressible member elevated, means for releasing said depressing member whereupon it may descend by gravity into contact with the upper end of the pin to depress same and enter the opening 10 of the topmost record, means associated with the depressing member for engaging the surface of the topmost record limiting the entry of the depressing member so that its lower end is located substantially at the underside of the topmost 15 record, and means for moving the depressible member laterally to slide the topmost record off the records therebeneath, which records are retained by the pin, whereby the records of the stack are removed successively at the different 20 levels they occupy in the stack and the pin moves upwardly above the records after the removal of a record.

34. In an automatic phonograph, in combination, a turntable adapted to rotate in a fixed plane 25 and adapted to support a stack of records to be played, a depressible center pin adapted to project upwardly through the openings in said records, resilient means tending to move the pin upwardly, and a depressing member movable above 30 said stack and adapted to engage said pin and move it downwardly to a position at or near the surface of the turntable, and means associated with said depressing member adapted to engage the surface of the topmost record to arrest said 35 member and limit its depression of the pin to a position at or near the lower surface of the topmost record.

35. In an automatic phonograph, in combination, a turntable adapted to rotate in a fixed plane 40 and adapted to support a stack of records to be played, a depressible center pin adapted to project upwardly through the openings in said records, resilient means tending to move the pin upwardly, and a depressing member movable 45 above said stack and adapted to engage said pin and move it downwardly to a position at or near the surface of the turntable, means associated with said depressing member adapted to engage the surface of the topmost record to arrest said 50 member and limit its depression of the pin to a position at or near the lower surface of the topmost record, and means for moving the depressing member transversely to slide the topmost record off the stack.

36. In an automatic phonograph, in combination, a turntable adapted to rotate in a fixed plane and adapted to support a stack of records to be played and removed successively, a depressible center pin adapted to project upwardly through the openings in said records, resilient means tending to move the pin upwardly, and a depressing member movable above said stack and capable of engaging said pin and moving downwardly through the position occupied by the records to 65 be removed and depressing said pin correspondingly, and means associated with said depressing member for engaging the top surface of the topmost record to arrest said depressing member and limit the depression of the pin substantially to 70 the lower surface of the topmost record.

37. In an automatic phonograph, in combination, a turntable adapted to rotate in a fixed plane and adapted to support a stack of records to be played and removed successively, a depressible 75

- center pin adapted to project upwardly through the openings in said records, resilient means tending to move the pin upwardly, and a depressing member movable above said stack and capable 5 of engaging said pin and moving downwardly through the position occupied by the records to be removed and depressing said pin correspondingly, means associated with said depressing member for engaging the top surface of the 10 topmost record to arrest said depressing member and limit the depression of the pin substantially to the lower surface of the topmost record, and means for moving the depressing member transversely to slide the topmost record off the stack.
- 15 38. In an automatic phonograph, in combination, a rotating turntable, a depressible pin centering a stack of records thereon, means for engaging the upper end of said pin and successively depressing the pin a distance increasing each 20 time by the thickness of one record, means for engaging the surface of the topmost record to limit the depression of said pin substantially to the lower surface of the topmost record, and resilient means urging said pin up again to the same 25 initial position after each depression.
39. In an automatic phonograph, in combination, a rotating turntable, a depressible pin centering a stack of records thereon to be removed one by one, means for engaging the upper end of 30 said pin and depressing it through the space occupied by the records to be removed, means associated with said engaging means for contacting the topmost record and limiting the depression of the pin substantially to the lower surface of the 35 topmost record, and resilient means urging said pin back to its initial position.
40. In an automatic phonograph, in combination, a turntable rotating in a fixed plane, a depressible centering pin adapted to project upwardly through a stack of records on said turntable, a spring normally projecting said pin upwardly beyond the stack of records, a depressing member adapted to engage said pin and depress it through the topmost record, and means associated 45 with the depressing member for engaging the topmost record and arresting the depressing member with the upper end of the depressible pin substantially at the level of the underside of the topmost record, said depressing member being 50 actuated impositively whereby it may be arrested at various levels for the removal of the records of the stack successively.
41. In an automatic phonograph, in combination, a turntable rotating in a fixed plane, a depressible centering pin adapted to project upwardly through a stack of records on said turntable, a spring normally projecting said pin upwardly beyond the stack of records, a depressing member adapted to engage said pin and depress it through the topmost record, means associated 55 with the depressing member for engaging the topmost record and arresting the depressing member with the upper end of the depressible pin substantially at the level of the underside of the topmost record, said depressing member being 60 actuated impositively whereby it may be arrested at various levels for the removal of the records of the stack successively, and means for moving the depressing member transversely to slide the topmost record off the stack.
- 65 42. In an automatic phonograph, in combination, a turntable rotating in a fixed plane, a depressible centering pin adapted to project up-
- wardly through a stack of records on said turntable, a spring normally projecting said pin upwardly beyond the stack of records, a depressing member adapted to engage said pin and depress it through the topmost record, and means associated 5 with the depressing member for engaging the topmost record and arresting the depressing member with the upper end of the depressible pin substantially at the level of the underside of the topmost record, said depressing member being 10 arranged to descend by gravity whereby it may be arrested at various levels for the removal of the records of the stack successively.
- 15 43. In an automatic phonograph, in combination, a turntable rotating in a fixed plane, a depressible centering pin adapted to project upwardly through a stack of records on said turntable, a spring normally projecting said pin upwardly beyond the stack of records, a depressing member adapted to engage said pin and depress it through the topmost record, means associated with the depressing member for engaging the topmost record and arresting the depressing member with the upper end of the depressible pin substantially at the level of the underside of the topmost record, said depressing member being 15 arranged to descend by gravity whereby it may be arrested at various levels for the removal of the records of the stack successively.
- 20 44. In an automatic phonograph, in combination, a turntable occupying a fixed plane and adapted to receive a stack of records, a central spindle carrying said turntable and having a bore at least equal in depth to the thickness of the stack of records, a pin slidably mounted within said bore, and a spring within said bore normally projecting the pin outwardly so that its upper end is above the topmost record, and a depressing member capable of engaging and depressing the depressible member through substantially all the space occupied by the stack of records.
- 25 45. In an automatic phonograph, in combination, a turntable adapted to receive a stack of records, means for continuously rotating said turntable during the successive playing and removal of said records, said turntable having a depressible centering pin extending through the openings in said records, means movable above said stack adapted to depress said pin sufficiently to free the topmost record, and means for displacing the topmost record from its centered position, whereupon the rotation of the turntable aids in removing said topmost record from the stack.
- 30 46. In an automatic phonograph, in combination, a turntable adapted to receive a stack of records, means for continuously rotating said turntable during the successive playing and removal of said records, said turntable having a depressible centering pin extending through the openings in said records, a record removing arm 35 movable above said stack adapted to depress said pin sufficiently to free the topmost record and to displace the topmost record from its centered position, whereupon the rotation of the turntable aids in removing said topmost record from the stack.

EDWARD F. ANDREWS.
